NECKTIE RACK

Archie J. McKelvie, Vancouver Island, British Columbia, Canada

Application April 26, 1939, Serial No. 270,215

2 Claims. (Cl. 211—89)

This invention relates to necktie racks and has for an object to provide a metal rack having clamp members spaced to engage neckties at spaced points in such manner as to hold the neckties without creasing or mutilating the same and at the same time prevent the ties from slipping off the rack.

A further object is to provide a necktie rack which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification:

Figure 1 is a perspective view of a necktie rack formed of resilient wire, in accordance with the invention.

Figure 2 is a side elevation of the rack shown in Figure 1 with a necktie applied thereto.

Figure 3 is a perspective view of a modified form of the necktie rack, formed of sheet metal.

Figure 4 is a detail sectional view taken on the line 4—4 of Figure 3.

Referring now to the drawing in which like characters of reference designate similar parts in the various views, 10 designates a sheet metal base of substantially rectangular contour having apertures 11 to receive nails or other securing means.

A pair of integral spaced arms 12 extend forwardly from the base at its lower edge. A pair of spaced clamping arms 13 extend downwardly from the upper edge of the base and are curved outwardly from the base, as shown at 14, to overlie the spaced arms 12 and coact therewith in forming clips for receiving neck ties.

As shown in Figure 4 the clamping portions 14 of the arms 13 are concave and the arms 12 are convex, so as not to injure or crease neck ties clamped therebetween. As shown in Figure 3, the tips of the clamping portions 14 and the tips of the arms 12 are bent reversely from each other to provide a flared entrance opening to permit the neckties to be easily applied to the clips.

A modified form of the invention shown in Figure 1 is formed of a single length of resilient wire. Briefly, the wire is bent to provide a base 15, a pair of spaced arms 16 extending forwardly

from the lower portion of the base, and a pair of spaced clamping arms 17 extending downwardly from the upper portion of the base and curved outwardly from the base, as shown at 18, to overlie the spaced arms 16 and coact therewith in 5 forming clips to receive neck ties 19.

The base is provided with loops 20 forming openings to receive nails 21 or similar securing means for attaching the necktie rack to a support 22. The tips of the clamping portions 18 10 of the arms 17 and the tips of the arms 16 are bent reversely to each other to provide a flared entrance opening to permit easy application of the neckties to the clips.

More specifically, the single length of resilient 15 wire may be first directed from its initial end 23 and reversed upon itself to form the loop 20 and left end 15 of the base, then directed downwardly and forwardly, then rearwardly and upwardly to form the left arm 17 and clamping portion 18 20 thereof, then directed toward the right end of the base, as shown at 24, to form the upper central portion of the base, then again directed downwardly and forwardly, then rearwardly, and upwardly to form the right arm 17 and clamping portion 18 25 thereof, then reversed upon itself to form the loop 20 and right end 15 of the base, then directed forwardly, then rearwardly to form the right arm 16 at the lower edge of the base, then directed toward the left end of the base as 30 shown at 25 to form the lower central portion of the base, then directed forwardly then rearwardly to form the left arm 16 at the lower edge of the base, and finally the terminal end 26 of the wire may be soldered or otherwise secured to 35 the initial end 23.

From the above description it is thought that the construction and operation of the invention will be fully understood without further explanation.

What is claimed is:

1. A necktie rack comprising a single length of resilient wire bent to form a base and loops at the ends of the base to receive securing devices, a plurality of integrally formed spaced arms extending forwardly from the base portion at its lower edge, and a plurality of clamping portions extending downwardly from the upper edge of the base, said clamping portions being curved outwardly and upwardly from the base portions 50 and overlying the spaced arms to coact with the arms in forming clips.

2. A necktie rack comprising a single length of resilient wire bent to form a base and loops at the ends of the base to receive securing devices, a 55

plurality of integrally formed spaced arms extending forwardly from the base portion at its lower edge, and a plurality of clamping portions extending downwardly from the upper edge of the base, said clamping portions being curved outwardly and upwardly from the base portions and overlying the spaced arms to coact with the arms in forming clips, the wire being first directed from its initial end and reversed upon itself to form the loop and left end of the base, then directed downwardly and forwardly, then rearwardly and upwardly to form the left arm and clamping portion thereof, then directed toward the right end of the base to form the upper central portion of

the base, then again directed downwardly and forwardly, then rearwardly and upwardly to form the right arm and clamping portion thereof, then reversed upon itself to form the loop and right end of the base, then directed forwardly, then rearwardly to form the right arm at the lower edge of the base, then directed toward the left end of the base to form the central lower portion of the base, then directed forwardly and then rearwardly to form the left arm at the lower edge of the base, and finally the terminal end being secured to the initial end of the wire. 5 10

ARCHIE J. MCKELVIE.
